NELSON BROS. MFG. CO., INC., OF SIOUX CITY, IOWA

OIL HEATER

Application filed December 9, 1929. Serial No. 412,678.

Our invention relates to oil heaters of the type illustrated in our companion applications, Serial Nos. 356,708 and 388,151, filed April 20, 1929 and August 24, 1929, respectively.

The present application has as its primary object to provide an oil heater having a heating capacity that is greatly increased over that of any of the plug type heater. By the 10 plug type heater, we mean a heater that is adapted to be substituted for the drain plug of a crank case or an oil container.

Another object of our invention is to provide a heater that may be operated either 15 from a storage battery or from an ordinary 110 volt power circuit or similar electrical transmission line for supplying power to homes.

A further object of the present invention is 20 to provide a heater having in addition to the above characteristics the advantages of simple, durable and inexpensive construction and especially that of ready assembly.

A further object is to provide a heater of 25 this type which is not only capable of being easily assembled but also of being easily torn down for repair.

Another object of the present invention is 30 to preserve the beneficial features of the heater of my companion applications in combination with the new advantageous features set forth above.

More particularly it is our aim to provide 35 a heater adapted to heat by direct contact with the oil of the container to which the heater is applied which does not project any substantial distance into the oil container and yet has a heating capacity which is not limited by this last requirement.

With these and other objects in view, our 40 invention consists in the construction, arrangement and combination of the various parts of our device, whereby the objects contemplated are attained, as hereinafter more fully set forth, pointed out in our claims, and illustrated in the accompanying drawings, in which:

Fig. 1 is a diagrammatical view of a portion 45 of an automobile dash and an electrical

circuit including the heater of the present invention.

Fig. 2 is a plan view of the heater with the top removed.

Fig. 3 is a vertical, sectional view through 55 the heater, taken on the line 3-3 of Fig. 2.

Fig. 4 is an inverted, plan view of a portion 60 of the top.

One of the requirements that has been found essential in the construction of a heater 65 of this type is that the heater should not project any substantial distance into the crank case of the vehicle to which it is applied. In most engines, the space within the crank case is so obstructed by working parts of the engine that the heater must be kept substantially at the inner level of the bottom of the 70 crank case.

It is possible to project the heater into the crank case just sufficiently to provide a raised 75 wall to prevent metallic particles and other foreign material being washed into the opening of the heater.

We have discovered that by utilizing a heating unit adapted to carry a 110 volt current that a heater constructed in accordance 80 with the principles of our companion applications may be made sufficiently powerful to not only take the ice film from the oil pump of a crank case but to warm the entire engine 85 by actually boiling the oil. Furthermore, we have discovered that this boiling of the oil is not detrimental to the oil but has a beneficial effect in that it will thoroughly vaporize all water and undesirable hydrocarbons such 90 as the lighter derivatives of benzine, gasoline and the like which find their way into the crank case of an automobile from the combustion chambers thereof. To state it more shortly, the boiling of the oil will distill off 95 the lighter hydrocarbons which cause dilution and rob the oil of its lubricating qualities. In order to utilize a 110 volt unit, however, more space is required than can be produced in a plug adapted to be received in the 100 drain opening of an oil container.

We have tried to solve this problem by extending the heating unit as far up into the oil container as possible and by making the shell of the plug as thin as possible. But

sufficient space could not be produced in this way to accommodate both heating units.

It finally occurred to us that it might be possible to place one of the heating units entirely outside of the oil container and still to obtain the necessary circulation of oil around the heating units.

From this concept there was evolved a solution to the problem of obtaining sufficient heating surface without obstructing the interior of the oil container. The idea was evolved into an auxiliary oil receptacle adapted to be positioned on the outside of the oil container and to communicate with the container by means of a neck portion adapted to be sealed against the oil container with its opening in communication with the opening in the oil container.

Circulation of oil from the container to the receptacle can thus be obtained, the oil passing from the container into the receptacle through one portion of the neck and after being heated flowing back into the oil container through another portion of the neck.

The structure embodied in this idea is very simple, comprising a receptacle pan A, having the bottom wall 10 and the side wall 11 terminating in an outwardly extended peripheral flange 12.

The other half of the receptacle is formed by a top B comprising a flat cover plate 13 and a neck 14, which is formed so as to fit the opening of an oil container 15. Since most drain openings will be threaded, the neck 14 is in most cases provided with threads to be received in the threads of the drain opening, thereby attaching the receptacle to the oil container. In this manner, the device serves as a plug for the drain opening, as in our companion applications.

The top B is attached to the pan A by means of screws or the like 16, extended through the cover plate 13 and threaded into the flange 12 or vice versa.

A gasket 17 is employed to seal the joint between the top and pan.

The heating units are mounted on a cross-shaped spider 18 of insulating material, the arms of which are extended as at 19 to be received in the recesses 20 in the side walls 11 of the pan A.

The top B is provided with a pair of lugs 21 (see Fig. 4) which are shaped to enter the recesses 20 and to clamp the portions 19 against the shoulders 22 formed at the bottoms of the recesses 20.

It will now be seen that the assembly of the device is speeded up considerably by the arrangement just described. The recesses 20 afford lateral support for the spider 18 and the lugs 21 and shoulders 22 securely hold the spider against vertical movement.

In assembling, it is only necessary to drop the spider into place to connect up the heating units to their various terminals, as will

later be described, and thence to secure the top member B in position.

The high tension heating unit comprises a coiled wire 23, threaded through openings 24 in the spider 18 and extended in the form of a spiral around the center of the spider.

The spider is made cross-shaped so that the oil may circulate between its arms and the major portions of the heating unit 23 are extended across the spaces between the arms of the spider so as to allow full circulation of the oil around these major portions of the unit.

Both ends of the heating unit 23 are connected to insulated terminals, one of which is shown in detail in Fig. 2. The terminal comprises a binding post 25, extended through an insulating sleeve 26, provided with insulated washers 27 and a locknut 28 and a binding post nut 29 to receive a current carrying wire. The end of the unit 23 is secured beneath the head of the binding post 25 on the inner side of the receptacle and is insulated from the receptacle by an insulating washer 30.

The low tension heating coil 31 is secured to the spider 18 at its center by means of a bolt 32 and a locknut 33. The bolt 32 is adapted to make electrical contact with the bottom of the receptacle, and to this end is threaded into a boss 34, formed on the bottom wall 10. The boss 34 serves to give support to the central region of the spider.

The upper end of the low tension unit 31 is connected as at 35 to a binding post 36 shown in Fig. 2.

Referring now to the diagram in Fig. 1, the low tension unit is grounded at one side to the engine of the vehicle, as indicated at 36 and is provided with a single current carrying wire 37, which extends through the medium of a dash switch 38 to the battery 39, which in turn is grounded as at 40 to the vehicle.

The high tension unit 23 is connected by a pair of current carrying wires 41 to a plug socket or similar electrical connection 42, installed in the instrument board 43.

The socket 42 is adapted to receive a conventional power line outlet plug 44, attached to a suitable extension cord 45, which in turn is connected to an ordinary power line in a garage.

With the arrangements just described, the heater may be energized from the high tension power line while the car is standing in a garage. The engine may be thoroughly warmed, taking no energy from the battery of the car preparatory to starting out on a cold morning. When the car is standing on the street or away from access to a power line, the chill may be taken from the oil pump by closing the switch 38 and taking the current from the battery 39 to energize the low tension unit 31.

It may now be noted that the low tension unit is arranged in the center of the recep-

tacle and extending up into the neck 14 in order to have the most direct access to the oil in the container or crank case. The high tension unit which is more powerful is disposed below and around the low tension unit. This arrangement also makes it possible to employ a spider support for the high tension unit, which is many times longer than the low tension unit and to utilize the majority of the area of the spider for the support of the high tension unit, only a small portion of the space being necessary to support the low tension unit. Furthermore this arrangement positions both the high and low tension units in symmetrical relation to the receptacle in order to assure uniform circulation of oil when either of the units are being used.

The shallow construction of the receptacle has the advantage of giving a maximum capacity to the receptacle with a minimum vertical displacement. It is, of course, undesirable to have the receptacle extend very far below the crank case of an automobile, owing to the possibility of injury from obstacles over which the vehicle may be passing.

The advantage of employing two heating units in a single plug member arises from the fact that there would be a tendency for the battery of a vehicle to be exhausted if the heater is at all times energized through the medium of a battery. A further advantage arises from the fact that with a high tension current, the entire engine may be warmed. A further advantage of embodying the two heating units together arises from the cheapness and simplicity of a construction embodying both units.

The symmetrical arrangements of the two units, one in spiral form and the other disposed therewithin makes it possible to utilize a low, flat receptacle to obtain uniform circulation of oil and to utilize in the most efficient manner the space within the receptacle whereby a maximum length of heating element may be employed.

The advantages residing in the use of a receptacle positioned outside of the oil container to which it is attached have already been explained but may be repeated briefly here as consisting in making it possible to provide sufficient space to accommodate a high tension heating unit adapted to have direct contact with the oil of the container without extending the unit upwardly into the container.

We claim as our invention:

1. In an oil heater for an oil container having an opening, a receptacle provided with an opening, high and low voltage heating units encased within the receptacle, and means for attaching the receptacle to the outer side of the container so as to form a closure for said container opening with

the two openings inter-communicating, whereby oil from the container may fill the receptacle and submerge the heating unit, the low voltage unit being grounded at one end to the receptacle, and the high voltage unit being insulated at both ends from the receptacle.

2. In combination with the storage battery, and crankcase of an automotive vehicle, a member adapted to serve as a plug for the crank case drain opening, high and low voltage heating units carried by said member, the low voltage unit being grounded at one end to the member, a switch controlled conductor connecting its other end to the battery, the high voltage unit being insulated at both ends from the member, an electrical connector mounted on the vehicle, and a pair of conductors connecting said connector to the high voltage unit, said connector being adapted to be connected with an electrical transmission line outlet.

3. In an oil heater, a receptacle comprising a pan and a top secured thereto, the pan having a side wall provided with interior recesses terminating in shoulders that are raised from the bottom of pan, a heating unit, an insulator for supporting said heating unit having portions received in said recesses and means extending into the pan and urged by the top into engagement with the insulator to secure the latter against said shoulders.

4. In an oil heater, a receptacle comprising a pan and a top secured thereto, shouldered means raised from the bottom of the pan on the inside thereof, a heating unit, an insulator supporting said heating unit seated on said shouldered means and thereby supported in spaced relation to the bottom of the pan and means held in place by the top and obstructing movement of the insulator in a direction away from said shouldered means.

5. In an oil heater, a receptacle comprising a pan and a top secured thereto, a heating unit, an insulator supporting said heating unit and loosely received in the pan and means held in place by the top and in turn serving to hold the insulator in position.

6. In an oil heater, a comparatively wide, shallow receptacle having a top provided with an opening adapted to communicate with an opening in an oil container, a comparatively wide insulator mounted in the receptacle substantially parallel to the bottom thereof, the insulator being provided with a plurality of openings, and a heating unit extended between and through said openings, and arranged alternately above and below the insulator, the major portion of the unit being above the insulator.

7. In an oil heater, a comparatively wide, shallow receptacle having a top provided with an opening adapted to communicate with an opening in an oil container, a comparatively wide insulator mounted in the

- receptacle substantially parallel to the bottom thereof, a high tension heating unit mounted on the insulator and occupying the outer area thereof, a low tension heating unit supported by the insulator and occupying the central area thereof, said low tension unit being disposed directly beneath the opening in the top of the receptacle. 5
8. In an oil heater, a receptacle, having an opening in its top adapted to communicate with an opening in an oil container, an insulator in the receptacle, a heating unit, a boss formed on the bottom of the receptacle and supporting the insulator from below, and 10 a metallic securing element serving to secure the unit to the insulator, extending into said boss, and serving to make an electrical connection between the receptacle and one end of the heating unit. 15
9. In an oil heater, a receptacle comprising a pan and a top secured thereto, the side wall of the pan being provided with oppositely disposed recesses terminating in shoulders spaced from the bottom of the pan, a heating 20 unit, an insulator supporting said unit provided with radiating arms, two of which are received in said recesses and a pair of lugs formed on the top extending into said recesses and engaging the arms of the insulator to 25 secure the latter in position spaced from the bottom of the pan. 30
10. In an oil heater, a receptacle which is comparatively wide and shallow, said receptacle having a top provided with an opening 35 adapted to communicate with an opening in an oil container, an insulator comprising a plurality of radiating arms mounted within the receptacle and spaced from the top and bottom thereof, spaces being thereby formed 40 between the arms of the insulator and the side walls of the receptacle to allow free circulation of fluid and a heating unit mounted on the insulator, said heating unit having portions extending across the spaces between 45 the arms of the insulator. 50
11. In an oil heater for an oil container having an opening, a receptacle provided with an opening, high and low voltage heating units encased within the receptacle, and 55 means for attaching the receptacle to the outer side of the container so as to form a closure for said container opening with the two openings intercommunicating, whereby oil from the container may fill the receptacle 60 and submerge the heating unit. 65
12. In an oil heater for an engine crank case having a threaded drain opening, a member adapted to serve as a plug for said opening, including a threaded neck adapted to be 70 received in the opening and a comparatively wide, shallow, enlarged receptacle attached to and positioned perpendicularly to the axis of the said neck and adapted to be supported by the crank case in a depending position 75 close to the bottom thereof, so as to be filled 80
- with oil therefrom, and a heating unit encased in the receptacle and adapted to have a heating contact with the oil therein. 85
13. In an oil heater, a receptacle comprising a pan and a top secured thereto, a heating unit, an insulator supporting said heating unit and loosely received in the pan, and elements secured to the top and depending into engagement with the insulator to hold it in position. 90
14. In an oil heater, a receptacle having a top provided with an opening adapted to communicate with an opening in an oil container, a flat insulator mounted in the receptacle substantially parallel to the bottom 95 thereof, the insulator being provided with a plurality of openings, and a heating unit extended through and between said openings, and arranged alternately above and below said insulator, the major portion of the unit being above the insulator. 100
15. In an oil heater, a comparatively wide, shallow receptacle having a top provided with an opening adapted to communicate with an opening in an oil container, a comparatively-wide insulator mounted in the receptacle substantially parallel to the bottom thereof, and high and low tension heating units mounted on the insulator one occupying the outer area thereof, and the other occupying the central region thereof and disposed beneath the opening in the top of the receptacle. 95
